UNITED STATES PATENT OFFICE.

BARNEY J. GAGNIER, OF DETROIT, MICHIGAN.

SUSPENDED RAILWAY.

SPECIFICATION forming part of Letters Patent No. 495,246, dated April 11, 1893.

Application filed January 17, 1893. Serial No. 458,633. (No model.)

To all whom it may concern:

Be it known that I, BARNEY J. GAGNIER, a citizen of the United States, residing at Detroit, in the county of Wayne and State of Michigan, have invented certain new and useful Improvements in Suspended Railways, of which the following is a specification, reference being had therein to the accompanying drawings.

The invention consists in the peculiar construction of an inclined way formed of two adjacent cables suspended at the ends, and a car suspended on that way upon wheels, the car being arranged to extend in a horizontal plane at all times of its travel, and an endless traction cable device for the car propelled by a motor at one end, and further in the peculiar construction, arrangement and combination of the various parts.

In the drawings, Figure 1 is a diagram elevation of my device as applied to crossing a river or ravine, the banks of which are at different elevations. Fig. 2 is an enlarged elevation of the car, and the derrick at one end showing the manner of applying the power. Fig. 3 is an end elevation of the car.

A and B are two cables, stretched taut from the tension bar C on a derrick D at one end, to a similar tension bar on a derrick E at the other end, the ends of the cables being anchored beyond the derrick. This gives me two cable tracks extended from the top of a high embankment on one side of the river and from a derrick on that bank to the low bank on the opposite side, the angle of inclination preferably being such that the car will move by gravity in one direction being pulled in the opposite direction by means hereinafter described.

F is a car of any suitable structure. This car is provided with a steel supporting frame, consisting of straps G and H, passing around the sides and bottom of the car and extending at each side above the top. These supporting straps extend above the car at different heights and near the top are provided with a suitable connecting frame I of any desired construction.

J are grooved wheels journaled in the supporting frames above the car at each side and adapted to run upon the suspended cables. A line connecting these wheels would be upon

an inclination to the roof of the car corresponding substantially to the inclination of the cables to the plane of the earth's surface, the result being that although the car is suspended from the inclined tracks, the car body will always retain its horizontal relation, while traveling up or down.

K and K' are drums journaled in the tops of the derricks and over which the traction cable L is wound, the two ends of the traction cable being secured to the opposite ends of the car.

M is the driving drum of the engine, preferably arranged in the base of the derrick D or in suitable proximity. N is a driving cable passing from the drum of the engine to a drum O on the shaft P of the cable drum K.

The parts being thus constructed their operation is as follows: The operator starting the engine will rotate the driving drum K which will start the driving cable L and propel the car along the supporting cables. If it is desired at any time to slacken the speed of the car, in its descent, it can be accomplished by having a suitable brake mechanism of any desired construction, such for instance as the brake blocks Q operated from a lever Q' extending in convenient proximity to the attendant, the operating mechanism of the brake being of any desired construction and which I do not consider necessary to herein fully show or describe, as any known brake mechanism may be adapted to the device.

I deem it advisable to automatically stop the engine at each end of the travel of the car and any suitable automatic means to accomplish this may be employed, that which I prefer being the tapering blocks R on the cable, which at the extreme positions of the car will strike the lever R', which lever is connected to the steam valve S of the engine (shown in diagram in Fig. 2) and close that valve, thereby shutting off the steam and stopping the engine and car. One of the blocks R is placed upon the propelling cable in close proximity to the car, while the other is placed at substantially the middle of that cable, as is plainly shown in Fig. 1, so that such middle block will strike the throwing out lever when the car approaches the derrick farthest from the propelling station.

What I claim as my invention is—

1. In a suspended railway, the combination of the derricks, two parallel cables suspended between the derricks upon an incline, and a car having its wheels at an angle to the body corresponding to the inclination of the rails, an endless propelling cable connected to opposite ends of the car, and a motor for actuating said cable, substantially as described.
2. In a suspended railway, the combination of the derricks, two separate cables suspended between the tops of the derricks, a car having suspending arms passing beneath it at each end and extending above to different heights, of wheels journaled in the top of said frames in a plane at an angle to the car body, corresponding substantially to the inclination of the cables, of drums journaled in the tops of the derricks, and an endless cable passing over the drums and connected at opposite

ends of the car and a motor for actuating the propelling cable, substantially as described.

3. In a suspended railway the combination with the suspended rails, a car having wheels journaled in the frame above the roof thereof and suspended from said rails, an endless cable passing over rollers at opposite ends of the way, and connected to opposite ends of the car, a motor at one end of the way for actuating said cable, and means on the cable for automatically stopping the motor when the car reaches the ends of the way, substantially as described.

In testimony whereof I affix my signature in presence of two witnesses.

BARNEY J. GAGNIER.
